Geo. S. Wheelock
ATTORNEY

UNITED STATES PATENT OFFICE

THADDEUS B. EIKER, OF JEFFERSON BARRACKS, MISSOURI

CARBURETOR

Application filed July 19, 1932. Serial No. 623,404.

The invention has particular reference to vaporizing means for carburetors, whereby to facilitate starting in cold weather and to render such devices more efficient in their idling operations.

The improvements forming the essence of this invention are especially applicable to carburetors and the like for internal combustion engines using liquid hydro-carbon fuel, and more particularly intended for use in motor vehicles, tractors, motor boats, etc. Most of such devices in the prior art embody an air intake tube in which is an adjustable butterfly valve, and a fuel nozzle communicating with the air intake tube at a point outwardly of the valve, that is, at the side of the valve farthest away from the engine. Such butterfly valves have usually been made slightly smaller in area than the cross-section of the air tube whereby to provide an annular space when the valve is positioned transversely of the tube axis, and thus allowing a limited mixture of air and fuel to pass the valve when adjusted to its idling or starting position. Difficulties have been experienced in obtaining a proper mixture of fuel and air, and particularly in obtaining a sufficiently rich mixture for starting the engine in cold weather, and these objectionable features of the prior art have been overcome by the present invention.

Numerous attempts have been made in the past to solve this problem by providing by-pass tubes and other such arrangements, some of which have communicated directly with the main fuel supply chamber and therefore constitute a fuel supply supplementary to the main fuel nozzle. Such a by-pass continues to operate after the butterfly valve is opened and therefore it has an undesirable effect upon the complete mixture after the engine has become warmed up and operating under normal conditions. Furthermore, some of such attempts have been unsuccessful because of the construction of the carburetor itself, principally in such devices where the fuel nozzle has been located a substantial distance away from the butterfly valve. Applicant has found that the effective suction within the air intake tube to draw fuel

from the fuel nozzle varies inversely as the distance between the fuel nozzle and the butterfly valve, and therefore he has found it highly desirable to locate his fuel nozzle co-axially with the butterfly valve. Such a carburetor has been fully disclosed in applicant's Patent No. 1,718,735, dated June 25, 1929.

An important object of the present invention is to overcome the above mentioned objectionable features of prior art carburetors by providing means for localizing or restricting the suction at a relatively small blind recess when the butterfly valve is substantially closed.

Another object is to provide such a device with means for varying the suction recess to compensate for changes in atmospheric conditions under which the engine operates.

Another object is to provide such a device as will be extremely simple in construction and therefore economical to produce, and one which will be a substantial improvement in the art.

Other objects and advantages will be apparent from the following description when taken in connection with the accompanying drawing, wherein the invention is shown by way of illustration, and wherein

Figure 1 is a top plan view of a carburetor embodying the present invention;

Figure 2 is a vertical, transverse, sectional view on the line 2-2 of Figure 1;

Figure 3 is a fragmentary, longitudinal, sectional view on the line 3-3 of Figure 2;

Figure 4 is a view similar to Figure 3, illustrating a modified form of the invention; and

Figure 5 is a similar view of still another form.

The invention may be applied to various types of carburetors but preferably one wherein the fuel nozzle is mounted in the axis of the adjustable butterfly valve. Referring particularly to Figures 1 and 2, such a carburetor includes an air intake tube 10 of the usual Venturi type having its inner end equipped with a flange 11 for attachment to the usual engine manifold or the like, and

having its outer end 12 open for the inward passage of air.

Preferably formed integral with the air intake tube 10 is the usual float controlled fuel chamber 13, which may be connected by a threaded pipe 14 to any suitable source of fuel supply, such as gasoline or other liquid hydro-carbons.

The fuel chamber 13 communicates with a well 15 which preferably depends below the air intake tube 10 and from which a tube 16 rises and terminates in a nozzle 17 which is disposed within the air intake tube 10. The passage of fuel through the nozzle 17 is controlled by a needle valve 18 carried on a threaded spindle 19, said spindle extending through a bushing 20 which is rotatable by means of a lever 21 and which is equipped with the usual abutments 22 for engagement with a stop member 23 on the outer side of the air inlet tube 10. The bushing 20 is provided with a reduced inner extremity 24 which extends into the air intake tube 10 and in opposed relation to the nozzle 17, as clearly shown in Figure 2, and secured to said reduced portion is a butterfly valve 25. The valve 25 is preferably in the form of a thin metallic disk whose periphery is adapted to fit snugly within the interior of the tube 10 when disposed transversely in the tube, such position being controlled by one of the abutments 22 coming against the stop member 23.

The tube 10 may preferably be formed with a boss 26 at a point preferably transversely intersecting the axis of the nozzle 17. Extending in a radial direction above said nozzle, the wall of the tube 10 is formed with a bore 27 extending through the boss 26. In the preferred embodiment the outer portion of the bore is enlarged and screw threaded for the reception of a threaded plug 29 which has a reduced diameter at its inner end 30 to snugly fit the interior of the bore 27. The diameter of the bore 27 is greater than the thickness of the butterfly valve 25, and the inner extremity of the plug 29 is spaced from the inner surface of the tube 10 in such a manner as to provide a blind suction recess 31 which spans the edge of the butterfly valve. That is to say, the width of the recess is greater than the thickness of the edge of the butterfly valve. If desired the inner end of the threaded plug 29 may also be formed with a circular recess 32 to assist in vaporization of the fuel, as will hereinafter be described, and a lock nut 33 cooperates with the threaded plug 29 and outer end of the boss 26 to lock the plug in its desired adjusted position.

In using the device, and particularly when starting the associated engine in cold weather, the valve 25 is positioned transversely to the axis of the air intake tube 10 in such a way that its adjacent edge substantially bisects the blind recess 31, and thereafter, as the en-

gine is turned over, the suction from the manifold to which the carburetor is attached will be localized, past the valve, at the relatively small recess 31, and in view of the juxtaposition of the fuel nozzle to the valve and the proximity of the blind recess thereto there will be caused a suitable quantity of fuel to be positively drawn upwardly from the nozzle 17, and, at the same time, air will be drawn inwardly in the tube 10 from its open end 12. The fuel and air thus drawn in, strike the edge of the butterfly valve and the bottom and side walls of the recess 31, and in so striking these parts the fuel becomes thoroughly vaporized and mixed with the air. Thus a sufficiently rich mixture is produced to be easily combustible within the cylinders of the engine, and after the engine is warmed up the butterfly valve 25 is opened to permit the passage of more air in proportion to the fuel drawn in.

As soon as the butterfly valve is adjusted to a point where its edge is beyond the limits of the recess 31, said recess is no longer operative, and from this it will be apparent that the localizing of the suction at the recess 31 will have no ill effect upon the normal operation of the motor and therefore will require no special adjustment of the needle valve 18.

In order to maintain the efficient idling operation and to facilitate starting under different atmospheric conditions, the depth of the recess may be varied by adjusting the plug 29 and locking it in its adjusted position by means of lock nut 33. Thus, in extremely cold weather it will be necessary to have the recess deeper than in warm weather, and this adjustment may be very quickly and easily made without disturbing the setting of the needle valve 18.

In Figure 4 a modified form of the invention is illustrated wherein the wall of the tube 10 and the boss 26 are provided with a threaded hole extending all the way through the same, said threaded hole being fitted with a plain screw 34 having its inner end 35 forming the bottom of the recess 36 which spans the edge of the butterfly valve 25. The operation of this form of the invention is the same as in the preferred embodiment and therefore need not be repeated.

Still another modification is shown in Figure 5, wherein a screw 37 has its inner end 38 extending to a point substantially flush with the inner surface of the tube 10 and formed with a cylindrical recess 39 of sufficient diameter to span the edge of the butterfly valve 25. When this form of the invention is used it may be desirable to provide each carburetor with a plurality of screws 37, each screw of the set having a different sized recess 39, said screws being selectively used to provide the proper recess for the particular operating conditions.

From the foregoing it will be evident that an extremely simple and effective means has been provided for localizing or restricting suction and forming a by-pass for the mixture at a relatively small portion of the periphery of the butterfly valve, and that such device, while being effective when the butterfly valve is closed, will not operate to disturb the needle valve 7 when the butterfly valve is open. Actual tests have proven that this device renders the carburetor more efficient, in that it produces a more thoroughly vaporized mixture and therefore economizes in the use of fuel by the engine.

Obviously, the invention is susceptible of further modification and the right is herein reserved to make changes in the details of construction and arrangement of parts within the scope of the appended claim.

Having thus described my invention, what is claimed is:—

In a carburetor, an air-intake tube, a butterfly valve adjustably mounted therein, a stationary fuel nozzle extending into said air-intake tube in definite juxtaposition to the butterfly valve, the nozzle being within the area of movement of the valve, and means for actuating the butterfly valve, said valve being adapted to snugly fit the interior of the air-intake tube when positioned transversely therein, the wall of the tube being apertured and fitted with a closure plug, the inner end of said plug being slightly spaced from the inner surface of the tube whereby to provide a blind recess for the by-pass of a fuel mixture when the valve is positioned across the tube to bisect the recess, said by-pass being ineffective when the valve is opened beyond the limits of the recess.

THADDEUS B. EIKER.
